FIRE EXTINGUISHER HAND HOLE AND COVER

Filed Aug. 25, 1930

INVENTOR.

EDWARD W. N. BOOSEY

Charles E. Nixon

ATTORNEY.

UNITED STATES PATENT OFFICE

EDWARD W. N. BOOSEY, OF DETROIT, MICHIGAN

FIRE EXTINGUISHER HAND HOLE AND COVER

Application filed August 25, 1930. Serial No. 477,574.

This invention relates to fire extinguisher hand holes and cover, and the object of the invention is to provide a simple and inexpensive hand hole and cover for floors or walls of buildings, factories, storage houses etc., especially where inflammable material may be stored.

A feature of the invention is to provide in a device of the character described, a sealed hand hole which under ordinary circumstances prevents the passage of water etc., from the floor through the hand hole and includes a ceiling plate in conjunction with the cover that is adjustable to flush with the ceiling or under side of the floor, and further to provide a cover member for such hand hole in which the distance of the ceiling plate from the cover member may be varied to correspond with the thickness of the floor.

These several objects and other novel features of the invention are hereinafter more fully described and claimed, and the preferred form of construction of a device embodying my invention is shown in the accompanying drawing in which—

Fig. 1 is a view showing my improved device when in use in the extinguishing of a fire.

Fig. 2 is a vertical section of the preferred form of construction of a device embodying my invention.

The device is more particularly adapted for use in the floors of buildings but may be utilized in the vertical walls of storage compartments if desired and in its preferred form consists of a cylindrical metal sleeve or tubular member 2 permanently fitted in the floor 1 or wall of a building or compartment as the case may be. The sleeve has a threaded end on which is threaded a channel member 3, and one purpose of threading the channel member on the sleeve is to permit longitudinal adjustment to correspond with various thicknesses of wall or floor. In this channel or raglet member is positioned the depending circular flange 4 of the cover 5. The raglet may be filled with any waterproofing material, preferably vaseline, whereby water on the floor surface is prevented from passing into the hand hole beneath the cover. The cover has a disappearing handle 6 consisting

of a U shaped rod, the legs of which pass through apertures provided therefor in the cover and have nuts 6^a on the threaded ends which extend into a cylindrical chamber 7 formed on the under or inner side of the cover. The cover member has a groove 6^b extending from one bolt aperture to the other into which the horizontal portion of the handle member may rest and a depression 6^c is formed in this groove permitting the operator to grasp the handle and raise the same.

To prevent fluid from passing into the hand hole through the apertures for the handle, the lower end of the cylindrical member 7 is provided with internal threads and a flanged cap 8 is threaded therein forming a closed receptacle which is also filled with waterproofing material such as vaseline. The cap 8 has a central hub 8^a threaded to receive a rod 9 which at its opposite end is threaded in a hub 10 of a ceiling plate 11. The plate 11 has a peripheral flange as shown and slidably fits the open end of the tubular member 2. By adjusting the cap member 8 in the cylindrical member 7 and by threading the rod 9 into or out of the hubs 8^a and 10 the distance of the ceiling plate from the cover member may be varied to correspond with various thicknesses of floors or walls. By this arrangement the plate 11 may be positioned practically flush with the ceiling of a room or with the inner face of a wall of the building in which the device is positioned and thereby prevents unsightly apertures in such surfaces.

In the case of a fire and, as is illustrated in Fig. 1, the firemen, instead of having to enter the compartment in which the fire exists and wherein heretofore, firemen and others have become suffocated with fumes, merely enters the upper floor above the fire, lifts the cover member 5 by means of a handle 6 from the position shown in Fig. 2 and this carries also the ceiling plate with it. The hand hole is of small diameter, approximately eight inches, through which the fire extinguisher hose may be inserted after removal of the cover and the fire extinguished without exposing the firemen to danger of suffocation or becoming trapped in the room.

where the fire is taking place or sprayed with inflammable material through an explosion. The device therefore enables the firemen to readily control the fire while shielded therefrom.

From the foregoing description it becomes evident that the device is simple in construction; inexpensive in character; that it provides a water tight sealed opening that is 10 instantaneously available for the purpose stated, and that the various objects of the invention are attained by the construction described.

Having thus briefly described my invention, its utility and mode of operation, what 15 I claim and desire to secure by Letters Patent of the United States is—

1. A fire extinguisher hand hole comprising a tubular member insertible in the floor 20 or wall of a building providing an aperture therethrough, said member being provided with a circumferential groove at the upper end, a cover therefor having a flange entering the groove, the groove providing a receptacle for sealing material, a plate attached to the cover and slidably fitting in the tubular member and removable therethrough by removal of the cover, and means for adjusting the plate relative to the cover to position 25 the same practically flush with the surface of the floor or wall opposite that occupied by the cover.

2. A fire extinguisher hand hole comprising an open ended metal member insertible 30 in the floor or wall of a building providing an aperture therethrough, a ring like member in threaded relation with the said open ended member at one end, said ring member having a groove in its upper face having its 35 outer peripheral wall greater in length than the inner wall, a cover member of a thickness approximately equal to the difference in length of walls of the ring member fitting within said outer wall and having a flange 40 extending into the said groove, the groove providing a receptacle for waterproofing material whereby fluid or liquid may not pass to beneath the cover into the open ended member, a handle for the cover member, 45 and a plate connected with the cover member slidably fitting the open ended member and positioned approximately flush with the 50 surface of a floor or wall in which the device is positioned.

3. A fire extinguisher hand hole comprising an open ended tubular member insertible in the floor or the wall of a building and providing an aperture therethrough, said member having a circularly grooved portion at the upper end, a cover member having a portion positioned in the said groove, the groove providing a chamber for a waterproofing material to prevent flow of liquids beneath the cover into the tubular member, a handle 60 for the said cover consisting of a U shaped

member, the legs of which extend through apertures provided in the cover, means on the ends of the handle member to prevent their withdrawal through the apertures therefor, and a sealed receptacle on the under side of the cover into which the handle ends extend.

4. A fire extinguisher hand hole comprising an open-ended tubular member insertible in the floor or the wall of a building and providing an aperture therethrough, said member having a circularly grooved portion at the upper end, a cover member having a portion positioned in the said groove, the groove providing a chamber for a waterproofing material to prevent flow of liquids beneath the cover into the tubular member, a handle for the said cover consisting of a U shaped member, the legs of which extend through apertures provided in the cover, means on the ends of the handle member to prevent their withdrawal through the apertures therefor, a sealed receptacle on the under side of the cover into which the handle ends extend, a plate attached to the receptacle and slidably fitting the tubular member, and means for adjusting the position of the plate flush with the wall surface at the end of the tubular member opposite the cover end.

5. A fire extinguisher hand hole comprising a tubular member insertible in the wall or floor of a building, the said tubular member having its upper end externally threaded, a channel member threaded thereon, the outer wall of which is of greater height than the inner wall, the threaded relation of the parts permitting an adjustment whereby the edge of the outer wall of the channel member and the opposite end of the tubular member may be positioned practically flush with the respective opposite sides of the floor or wall in which the member is positioned, a cover member fitting within the outer wall of the channel member and resting on the inner wall thereof, said cover member having a flange extending into the channel, said channel providing a receptacle for a non-congealing material to prevent ingress of water or other liquid into a hand hole, a handle for the cover member consisting of a U shaped 100 rod, the legs of which extend through apertures provided therefor in the cover, said cover further having a groove between the apertures to receive the connecting portion 105 of the handle between the legs, the ends of the legs being provided with means preventing removal through the apertures therefor, a cylindrical member connected with the cover into which the handle ends extend, a cap member in threaded relation with the 110 said cylindrical portion of the cover providing a closed chamber for containing a non-congealing material to prevent passage of liquid through the handle, apertures of the 115 cover into the hand hole, a plate slidably 120 fitting the cylindrical member, and means for adjusting the position of the plate flush with the wall surface at the end of the cylindrical member.

6. A fire extinguisher hand hole comprising an open ended tubular member insertible in the floor or the wall of a building and providing an aperture therethrough, said member having a circularly grooved portion at the upper end, a cover member having a portion positioned in the said groove, the groove providing a chamber for a waterproofing material to prevent flow of liquids beneath the cover into the tubular member, a handle 125 for the said cover consisting of a U shaped member, the legs of which extend through apertures provided in the cover, means on the ends of the handle member to prevent their withdrawal through the apertures therefor, a cylindrical member connected with the cover into which the handle ends extend, a cap member in threaded relation with the 130 said cylindrical portion of the cover providing a closed chamber for containing a non-congealing material to prevent passage of liquid through the handle, apertures of the cover into the hand hole, a plate slidably

fitting the tubular member, a rod in threaded relation with the plate at one end and with the cap at the other, the threaded rod and threaded relation of the cap with the 5 cylindrical member providing means for adjusting the plate in the tubular member to a position practically flush with the inner face of a wall or under surface of a floor in which the device is positioned.

10 6. A fire extinguisher hand hole comprising a tubular member positioned in the floor or wall of a building providing an aperture therethrough, a cover member for closing the upper end, a plate attached to the cover member 15 in spaced relation therewith and insertible in the tubular member by the placing of the cover thereon, said plate being positioned approximately flush with the surface of the floor or wall opposite that occupied 20 by the cover also closing the aperture provided by the tubular member.

In testimony whereof, I sign this specification.

EDWARD W. N. BOOSEY.
